(57) **CLAIM**

The ornamental design for a data input machine, as shown and described.

DESCRIPTION

FIG. 1 is a perspective view of a data input machine showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof; and,

FIG. 8 is sectional view taken from 8-8 in FIG. 3.

The features shown in broken lines depict environmental subject matter only and form no part of the claimed design.

1 Claim, 8 Drawing Sheets[FIG. 1]

[FIG. 2]

[FIG.3]

[FIG.4]

[FIG.5]

[FIG.6]
